(57) **CLAIM**

The ornamental design for a beverage maker appliance, as shown and described.

DESCRIPTION

FIG. 1 is a front and right side perspective view of a beverage maker appliance showing our new design;
FIG. 2 is a front elevational view thereof;
FIG. 3 is a top plan view thereof;
FIG. 4 is a bottom plan view thereof;

FIG. 5 is a right side elevational view thereof; and,
FIG. 6 is a left side elevational view thereof.

The broken lines shown in the drawing disclosure are for illustrative purposes only and form no part of the claimed design.
